UNITED STATES PATENT OFFICE.

CHARLES A. GENUNG, OF WATERLOO, NEW YORK.

SUPPLEMENTAL BOTTOM FOR TRANSPORTATION-CASKETS.

SPECIFICATION forming part of Letters Patent No. 744,186, dated November 17, 1903.

Application filed August 2, 1898. Serial No. 687,554. (No model.)

To all whom it may concern:

Be it known that I, CHARLES A. GENUNG, of Waterloo, in the county of Seneca, in the State of New York, have invented new and useful Improvements in Supplemental Bottoms for Transportation-Caskets, of which the following, taken in connection with the accompanying drawings, is a full, clear, and exact description.

10 My invention has for its object the production of a supplemental bottom for a transportation-casket which is particularly applicable in connection with an inclosing case for embalming, cooling, and shipping a body; and 15 to this end it consists in the combination, construction, and arrangement of the component parts of a supplemental bottom for a transportation-casket, as hereinafter fully described, and pointed out in the claims.

20 In describing this invention reference is had to the accompanying drawings, forming part of this specification, in which like letters indicate corresponding parts in all the views.

Figures 1 and 2 are respectively top plan and 25 side elevation of my improved supplemental bottom for a transportation-casket, said bottom being shown in Fig. 1 as substantially flat and in Fig. 2 as in its operative position. Figs. 3, 4, and 5 are vertical sectional views 30 taken, respectively, on lines 3 3, 4 4, and 5 5, Fig. 1. Figs. 6 and 7 are isometric views of the detached foot-rest and head-block of my invention. Figs. 8 and 9 are isometric views 35 of an engaging bar and a brace for holding the adjustable leg of my invention in its operative position.

My supplemental bottom for a transportation-casket preferably consists of a frame A, an adjustable leg B, a head-rest C, and a foot-rest D. The frame A is generally provided 40 with handles a and is usually composed of lengthwise bars a' a' and cross-bars a², having their adjacent longitudinal edges separated and their opposite ends secured upon 45 the upper faces of the bars a' a'. Said frame is preferably formed with a recess a³ in its lower face, an opening a⁴, extending downwardly from one end of its top face, and lengthwise bars a⁵, extending across said opening. The recess a³ extends longitudinally between the lengthwise bars a' a'. The opening a⁴ is interposed between two of the cross-bars

a², which are separated a greater distance than the remaining cross-bars, as best seen in Figs. 1, 3, and 4, and the bars a⁵ are suitably secured to adjacent cross-bars a² and are provided with a plurality of transverse shoulders a⁶ and lengthwise cut-outs a⁷.

The adjustable leg B is of any desirable form, size, and construction and may be movable into the recess a³ when desired. The foot of the leg B is normally supported in the same plane as one end of the frame A when my supplemental bottom is in its operative position and is movable into and out of the recess a³, and the opposite extremity of said leg is pivoted in the recess a³ between the bars a' a' and serves to raise and lower the corresponding end of the frame A. When the leg B is projected from the recess and its foot 70 is engaged by the floor, one end of the frame is raised and the opposite end or foot rests on the floor in the same plane as the foot of said leg. The leg B may be held in its adjusted position by any suitable means, (here illustrated as engaging bars a⁸ and braces b.) The bars a⁸ preferably extend lengthwise of the frame A, are suitably secured to the inner faces of the bars a' a' of said frame in alignment with the opening a⁴, and form, essentially, portions of the opposite sides of the recess a³. Said bars a⁸ are generally formed with lengthwise slots a⁹, having their upper walls provided with engaging shoulders a¹⁰. The braces b are pivoted at corresponding 85 ends to the leg B, and their opposite ends are preferably formed with lateral extensions b', handpieces b², and spring-arms b³, having lateral extensions b⁴. The lateral extensions b' b⁴ of the braces b are movable in the slots a⁹, as best seen in Fig. 4, the extensions b' being normally engaged with the shoulders a¹⁰ and the extensions b⁴ with the opposite walls of the slots a⁹. When it is desired to adjust the leg B, the handpieces b² are depressed against the action of the spring-arms b³ for forcing the extensions b' out of engagement with the shoulders a¹⁰, whereupon said handpieces are moved lengthwise of the frame A until the desired adjustment of the leg B 100 is effected.

The head-rest C generally extends longitudinally between the lengthwise bars a' a' of the frame A, is interposed between the two

cross-bars a^2 , arranged at opposite sides of the opening a^4 , and is usually composed of lengthwise bars c and cross-bars c' . One extremity of the head-rest is pivoted to the inner ends 5 of the lengthwise bars a^5 of the frame A in proximity to the cross-bar a^2 , forming the inner wall of the opening a^4 in said frame, and the opposite extremity of the head-rest is movable above the frame and is usually provided with a head-block C'.

The means for holding the head-rest in its normal position preferably consists of a supporting member c^2 , formed substantially U-shaped and having its intermediate portion 15 engaged with the shoulders a^6 and its opposite branches movable into the cut-outs a^7 of the bars a^5 in a plane substantially parallel with said bars.

The head-block C' is preferably formed 20 with a concave upper face c^8 , a convex lower face c^4 , and projecting arms c^5 . The face c^8 closely fits the adjacent portion of a body supported by my invention, and the face c^4 rests upon the upper face of the head-rest C and 25 permits more or less rocking movement of the head-block C' independently of the head-rest for facilitating the support of said adjacent portion of a body. The arms c^5 are passed through enlargements of openings c^6 , 30 formed in the free end of the head-rest, and are provided with shoulders which detachably engage the under face of the contiguous portion of said head-rest for normally preventing detachment of the head-block C'. The 35 head-rest C is particularly applicable for my supplemental bottom for transportation-caskets; but it is obvious that any other suitable head-rest may be used, if desired.

The foot-rest D is preferably adjustably 40 mounted on the frame A and composed of a central section d and side sections d' , having corresponding ends hinged to the opposite extremities of the section d and their other ends provided with arms d^2 , movable laterally between the cross-bars a^2 of the frame A 45 and provided with shoulders d^3 for detachably engaging the under faces of said cross-bars and holding the foot-rest in its adjusted position. Said foot-rest is also particularly 50 applicable for my supplemental bottom for a transportation-casket; but it is obvious that any other suitable foot-rest may be used with said supplemental bottom.

My supplemental bottom for a transportation-casket will now be readily understood 55 upon reference to the foregoing description and the accompanying drawings, and it will be readily apparent that the detail construction and arrangement of its component parts 60 may be more or less varied without departing from the spirit of my invention.

Having thus fully described my invention, what I claim as new, and desire to secure by Letters Patent, is—

65 1. In a supplemental bottom for a transportation-casket, the combination of a frame provided with shoulders, an adjustable leg

having its foot normally supported in the same plane as one end of the frame and its opposite extremity secured to the frame in 70 proximity to the other end thereof for raising and lowering said other end of the frame, and a brace pivoted to the adjustable leg and movable into engagement with said shoulders, substantially as and for the purpose described. 75

2. A supplemental bottom for a transportation-casket, the same comprising a frame provided with a plurality of shoulders, an adjustable leg having its foot normally supported in the same plane as one end of the frame and its opposite extremity secured to the frame in proximity to the other end thereof for raising and lowering the frame, and a brace having one end connected to the leg 80 and its opposite end movable into engagement with the shoulders, said brace being provided with means for holding its said opposite end in engagement with the shoulders, substantially as and for the purpose set 85 forth.

3. A supplemental bottom for a transportation-casket, the same comprising a frame formed with a substantially lengthwise slot having one wall thereof provided with a plurality of shoulders, an adjustable leg having its foot supported in the same plane as one 90 end of the frame and its opposite extremity secured to the frame in proximity to the other end thereof for raising and lowering the same, and a brace having one end pivoted to the leg and its other end provided with a lateral extension movable in the slot for engaging the shoulders, and a spring-arm having a lateral extension movable in the slot for engaging the wall thereof opposite to said shoulders, substantially as and for the purpose set 95 forth.

4. A supplemental bottom for a transportation-casket, the same comprising a frame 100 formed with a recess in its lower face, and a substantially lengthwise slot formed in one side of the recess and having one wall thereof provided with a plurality of shoulders, an adjustable leg having its foot supported in the 105 same plane as one end of the frame and movable into and out of the recess and its opposite extremity secured to the frame for raising and lowering the same, and a brace having one end pivoted to the leg and its other 110 end movable into engagement with the shoulders and provided with a spring-arm for engaging the wall of the slot of the frame opposite to said shoulders, substantially as and for the purpose specified. 115

In testimony whereof I have hereunto signed my name, in the presence of two attesting witnesses, at Syracuse, in the county of Onondaga, in the State of New York, this 20th day of July, 1898.

CHARLES A. GENUNG.
